(57) **CLAIM**

The ornamental design of magnetized side seams for a clothing garment, as shown and described.

DESCRIPTION

FIG. 1 is a left-front perspective view of magnetized side seams for a clothing garment, wherein the side seams are in a closed position, showing the present design.

FIG. 2 is a front view of the magnetized side seams for a clothing garment wherein the side seams are in a closed position.

FIG. 3 is a rear view of the magnetized side seams for a clothing garment wherein the side seams are in a closed position.

FIG. 4 is a right-side view of the magnetized side seams for a clothing garment wherein the side seams are in a closed position.

FIG. 5 is a left side-view of the magnetized side seams for a clothing garment wherein the side seams are in a closed position.

FIG. 6 is a top view of the magnetized side seams for a clothing garment wherein the side seams are in a closed position.

FIG. 7 is a bottom view of the clothing garment with magnetized side wherein the side seams are in a closed position.

FIG. 8 is a left-front perspective view of the magnetized side seams for a clothing garment, wherein the side seams are in an open position; and,

FIG. 9 is a bottom perspective view of the magnetized side seams for a clothing garment, wherein one of the side seams is in an open position.

The evenly spaced broken lines in the drawings are included for the purpose of illustrating portions of the clothing garment that form no part of the claimed design. The dot-dash-dot broken lines in the drawings are included for the purpose of defining the boundary lines of the claim, it being understood that the claimed design lies between the boundary lines and that the dot-dash-dot broken lines themselves form no part of the claimed design. The broken lines surrounding the magnetic buttons on the side seams depict stitching which are portions of the article that form no part of the claimed design.
